(57) **ABSTRACT**
This invention relates to a new and distinct variety of strawberry plant named 'Constitution'. This new strawberry plant named 'Constitution' is primarily adapted to the growing conditions of West Central Florida, and is primarily characterized by its achenes typically set even with or just below the surface of the fruit, vigorous plant habit, very high marketable yield, early time of first flower and fruit, and large berry size.

4 Drawing Sheets

1

Latin name of the genus and species of the plant claimed:
Fragaria ananassa.

Variety denomination: 'CONSTITUTION'.

BACKGROUND OF THE INVENTION

The present invention relates to a new and distinct strawberry variety named 'CONSTITUTION'. This new variety is a result of a controlled cross made in 2012 in an ongoing breeding program between the unpatented strawberry variety designated 'Red Merlin' as the seed (female) parent, and the unreleased, unpatented strawberry breeding selection designated 'BG-5.321' as the pollen (male) parent. The variety is botanically known as *Fragaria ananassa*.

The seedling resulting from the aforementioned cross was selected from a controlled breeding plot in Hillsborough County, Fla. in the fall/winter of 2013-2014. After its selection, the new variety was asexually propagated by stolons in both Siskiyou County, Calif. and San Joaquin County, Calif. The new variety was extensively tested over the next several years in fruiting fields in Hillsborough County, Fla. This propagation has demonstrated that the combination of traits disclosed herein as characterizing the new variety are fixed and remain true-to-type through successive generations of asexual reproduction.

BRIEF SUMMARY OF THE INVENTION

'CONSTITUTION' is primarily adapted to the climate and growing conditions of West Central Florida. The subtropical climate of West Central Florida provides the day

2

length and moderate temperatures needed to produce an early yielding, vigorous plant and maintain fruit quality during the fall and winter production months.

5 The following traits have been repeatedly observed and are determined to be unique characteristics of 'CONSTITUTION', which in combination distinguish this strawberry plant as a new and distinct variety:

- 10 1. Achenes typically set even with or just below the surface of the fruit;
2. Vigorous plant habit;
3. Very high marketable yield;
15 4. Early time of first flower and fruit; and
5. Large berry size.

20 'Florida Brilliance' (U.S. Plant Pat. No. 30,564) is currently the dominant strawberry variety in Hillsborough County, Fla. The fruits of 'CONSTITUTION' are similar in color, flavor, and firmness to 'Florida Brilliance', but the fruits of 'CONSTITUTION' are more elongated and the plant is more vigorous. The achenes of 'Florida Brilliance' are slightly more sunken than those of 'CONSTITUTION' and its plant architecture is more open. In side-by-side comparisons from the 2020-2021 season (Nov. 19, 2020 to Feb. 19, 2021) 'CONSTITUTION' compares with 'Florida Brilliance' (U.S. Plant Pat. No. 30,564) in the following 25 combination of characteristics as described in Table 1.

TABLE 1

Characteristic	'SB_12_101-108'	'Florida Brilliance' (U.S. Plant Pat. No. 30,564)
November marketable yield (gm/plt)	54	20
Season marketable yield (gm/plt)	273	269
November average berry size (gm)	18.2	12.7
Season average berry size (gm)	21.1	24.0
Average runners/plant	1.9	1.2

For identification, a series of molecular markers have been determined for this new variety.

'CONSTITUTION' differs from its parents, 'Red Merlin' and 'BG-5.321' by the following combination of characteristics as described in Tables 2 and 3.

TABLE 2

Characteristic	'SB_12_101-108'	'Red Merlin'
Fruit: size	Large	Medium
Fruit: marketable yield	Very high	Medium
Fruit: flavor	Fair	Fair to good
Fruit: seed position	Slightly below to even with surface	Even with surface

TABLE 3

Characteristic	'S6_12_101-108'	'BG-5.321'
Fruit: size	Large	Very large
Fruit: marketable yield	Very high	High
Fruit: early yield	Very high	High
Fruit: continuous yielding	Gaps mid-season	Continuous

BRIEF DESCRIPTIONS OF THE PHOTOGRAPHS

The accompanying color photographs illustrate the overall appearance of typical specimens of the new strawberry variety 'CONSTITUTION' at various stages of development, as true as it is reasonably possible with color reproductions of this type. Color in the photographs may differ slightly from the color value cited in the botanical descriptions which accurately describe the color of 'CONSTITUTION'. The depicted plant and plant parts of the new strawberry variety 'CONSTITUTION' are approximately four months old. The photographs were taken in Hillsborough County, Fla.

FIG. 1 shows typical fruiting field characteristics of 'CONSTITUTION', taken in the month of February 2021;

FIG. 2 shows a close-up view of a typical plant of 'CONSTITUTION', taken in the month of February 2021;

FIG. 3 shows typical mature and immature field fruit of 'CONSTITUTION', taken in the month of February 2021; and

FIG. 4 shows typical internal and external mature fruit characteristics of 'CONSTITUTION', taken in the month of February 2021.

DETAILED BOTANICAL DESCRIPTION

The new variety 'CONSTITUTION' has not been observed under all possible environmental conditions. The

characteristics of the new variety 'CONSTITUTION' may vary in detail, depending upon variations in environmental factors, including weather (temperature, humidity and light intensity), day length, soil type and location. In addition, the characteristics of any parental variety or comparison variety included in Table 1 of the present invention may vary in detail, depending upon variations in environmental factors, including weather (temperature, humidity and light intensity), day length, soil type and location.

The aforementioned photographs, together with the following description of the new variety 'CONSTITUTION', unless otherwise noted, are based on observations taken during the 2020-2021 growing season in Hillsborough County, Fla. These measurements and ratings were taken from plants of 'CONSTITUTION' dug from a high-elevation nursery located in Siskiyou County, Calif. during mid-September 2020 and planted approximately four to five days later in Hillsborough County, Fla. The approximate age of the observed plants is four months. Yield observations including average weight and marketable yield, along with fruit quality characteristics including soluble solids, were measured during the 2020-2021 growing season. Flower measurements and characteristics are from secondary flowers unless otherwise noted. Fruit characteristics and measurements are from secondary fruit, unless otherwise noted.

Where noted, color terminology follows The Royal Horticultural Society Colour Chart, London (2015).

The following characteristics describe fruit, plant, stolon, foliage, fruiting truss, flower, reproductive organs and pest and disease characteristics of the new strawberry 'CONSTITUTION'.

Fruit characteristics:

Color of mature fruit.—RHS 46B.

Color of internal flesh (excluding core).—RHS 42A.

Color of core.—RHS 49D.

Average length (cm).—4.2.

Average width (cm).—3.3.

Size.—Large.

Average length/width ratio.—1.3 (ranges from as long as broad to slightly longer than broad).

Average calyx diameter (cm).—4.3.

Season average weight (gm).—21.1.

Achene color, shaded side.—RHS 183C.

Achene color, sun-exposed side.—RHS 153B.

Average achene weight (mg).—0.6.

Average achenes per berry.—457.

Average achene length (mm).—2.2.

Average achene width (mm).—0.9.

Season marketable yield (gm/plant).—273.

Predominant shape.—Conical.

Difference in shape between primary and secondary fruit.—Ranges from moderate to large.

Band without achenes.—Narrow.

Evenness of surface.—Even.

Evenness of color.—Even or very slightly uneven.

Glossiness.—Ranges from medium to strong.

Insertion of achenes.—Even to slightly below surface.

Position of calyx attachment.—Inserted.

Attitude of sepals.—Outward.

Size of calyx in relation to fruit diameter.—Larger.

Adherence of calyx (when fully ripe).—Strong.

Firmness of flesh.—Firm.

Distribution of red color of the flesh.—Marginal and mildly central.

Hollow center expression.—Minimal.

<i>Average cavity length (mm).</i> —9.3.		<i>Size of bract leaflets (mm²).</i> —5.3.
<i>Average cavity width (mm).</i> —2.5.		<i>Pubescence.</i> —Moderate.
<i>Time of first flowering.</i> —Early (early to mid-October in Hillsborough County, Fla.).	5	<i>Stipule characteristics:</i>
<i>Flowering season.</i> —October–February.		<i>Color.</i> —RHS 145C (yellow green group).
<i>Time of first fruit.</i> —Early (mid-November in Hillsborough County, Fla.).	10	<i>Anthocyanin coloration.</i> —RHS 182C (greyed red group).
<i>Fruiting season.</i> —November–March.		<i>Anthocyanin intensity.</i> —Moderate.
<i>Post-harvest fruit longevity.</i> —9–11 days if stored according to industry standards.	10	<i>Average length (mm).</i> —30.1.
<i>Type of bearing.</i> —Not remontant.		<i>Average width (mm).</i> —8.34.
<i>Plant characteristics:</i>		<i>Base descriptor.</i> —Truncate.
<i>Average height (cm).</i> —20.2.		<i>Apex descriptor.</i> —Obtuse.
<i>Average spread (cm).</i> —34.6.	15	<i>Shape.</i> —Triangular.
<i>Size.</i> —Large.		<i>Margin.</i> —Smooth.
<i>Habit.</i> —Upright.		<i>Texture.</i> —Moderate to smooth.
<i>Density.</i> —High.		<i>Fruiting truss characteristics:</i>
<i>Vigor.</i> —High.		<i>Anthocyanin coloration.</i> —147B.
<i>Stolon characteristics:</i>	20	<i>Anthocyanin intensity.</i> —Light.
<i>Color.</i> —RHS 145A (yellow green group).		<i>Pubescence.</i> —Light to moderate.
<i>Anthocyanin coloration.</i> —RHS 176B (greyed orange group).		<i>Attitude at first pick.</i> —Prostrate.
<i>Anthocyanin intensity.</i> —Moderately intense.		<i>Position relative to foliage.</i> —Ranges from level with to above.
<i>Pubescence.</i> —Moderately Dense.	25	<i>Flower quantity (average per plant season long).</i> —20–40 (medium to high).
<i>Attitude of hairs.</i> —Slightly outward.		<i>Average fruits per truss.</i> —19.2.
<i>Average quantity in nursery (per square foot).</i> —13.5.		<i>Pedicel attitude of hairs.</i> —Slightly outward.
<i>Average diameter at the bract (mm).</i> —2.2.		<i>Average pedicel length (cm).</i> —21.0.
<i>Terminal leaflet characteristics:</i>		<i>Average pedicel diameter (mm).</i> —1.9.
<i>Color of upper surface.</i> —RHS 147A (medium yellow green).	30	<i>Pedicel texture.</i> —Moderate to smooth.
<i>Color of underside.</i> —RHS 147B (yellow green group).		<i>Pedicel color.</i> —RHS N144B (yellow green group).
<i>Average length (cm).</i> —7.3.		<i>Average peduncle length (cm).</i> —N/A.
<i>Average width (cm).</i> —6.75.		<i>Average peduncle diameter (mm).</i> —N/A.
<i>Average area terminal (cm²).</i> —49.3.	35	<i>Peduncle texture.</i> —N/A.
<i>Average length/width ratio.</i> —1.08 (longer than broad).		<i>Peduncle color.</i> —N/A.
<i>Shape of base.</i> —Obtuse.		<i>Flower characteristics:</i>
<i>Margins (shape of teeth).</i> —Serrate to crenate.		<i>Flower bud shape.</i> —Pyriform.
<i>Average serrations per leaf.</i> —20.1.		<i>Average flower bud length (mm).</i> —18.9.
<i>Foliage characteristics:</i>	40	<i>Average flower bud diameter (mm).</i> —5.7.
<i>Color of upper surface.</i> —RHS 147A (medium yellow green).		<i>Flower bud color.</i> —RHS 145A (yellow green group).
<i>Color of underside.</i> —RHS 147B (yellow green group).		<i>Flower depth (mm).</i> —17.5.
<i>Number of leaflets.</i> —3.		<i>Corolla (flower) average diameter (mm).</i> —32.1 (ranges from medium to large).
<i>Leaf size.</i> —Small to medium.	45	<i>Upper petal color.</i> —RHS NN155A (white group).
<i>Average length (cm).</i> —9.15.		<i>Lower petal color.</i> —RHS NN155A (white group).
<i>Average width (cm).</i> —11.80.		<i>Petal shape.</i> —Orbicular.
<i>Average area foliage (cm²).</i> —107.97.		<i>Petal apex descriptor.</i> —Rounded.
<i>Shape in cross section.</i> —Slightly concave.		<i>Petal margin.</i> —Smooth.
<i>Texture/interveinal blistering.</i> —Ranges from light to medium.	50	<i>Petal base.</i> —Decurrent.
<i>Leaf glossiness.</i> —Medium.		<i>Petal texture.</i> —Smooth.
<i>Leaf variegation.</i> —Absent.		<i>Petal average length (mm).</i> —13.3.
<i>Venation pattern.</i> —Pinnate/cross venulate.		<i>Petal average width (mm).</i> —11.8.
<i>Apex descriptor.</i> —Obtuse.	55	<i>Petal average length/width ratio.</i> —1.1 (as long as broad).
<i>Petiole characteristics:</i>		<i>Average petals per flower.</i> —5.9.
<i>Petiole color.</i> —RHS 144D (yellow green group).		<i>Relative position of petals (flowers with 5 or 6 petals).</i> —Overlapping.
<i>Average length (cm).</i> —11.65.		<i>Upper sepal color.</i> —RHS 137A (green group).
<i>Average diameter (mm).</i> —1.88.		<i>Lower sepal color.</i> —RHS N138B (yellow green group).
<i>Petiolule color.</i> —RHS 144D (yellow green group).	60	<i>Sepal shape.</i> —Lanceolate.
<i>Petiolule average length (mm).</i> —5.43.		<i>Sepal apex descriptor.</i> —Acute.
<i>Average petiolule diameter (mm).</i> —1.3.		<i>Sepal margin.</i> —Smooth to serrate.
<i>Attitude of hairs.</i> —Slightly outward.		<i>Sepal texture.</i> —Moderately smooth.
<i>Texture.</i> —Moderate to smooth.		<i>Sepal average length (mm).</i> —16.6.
<i>Frequency of bract leaflets.</i> —Ranges from 0 to 2 (80% occurrence).	65	<i>Sepal average width (mm).</i> —7.4.
		<i>Sepal average length/width ratio.</i> —2.2.

US PP34,737 P2

7

Average sepals per flower.—11.7.
Calyx average diameter (mm).—38.7.
Size of calyx relative to corolla.—Larger.
Size of inner calyx relative to outer calyx.—Same.
Reproductive organs:
Receptacle color.—RHS 1B.
Pollen color.—RHS 15A (yellow group).
Stamen.—Present.
Average filament length (mm).—2.6.
Filament color.—RHS 145C.
Average anther length (mm).—1.5.
Anther shape.—Ovoid.
Anther color.—RHS 15A (yellow orange color).

8

Average pistils per flower.—457.
Pistil length (mm).—0.5-2.5.
Style length (mm).—<2.5.
Style color.—RHS 1B.
5 *Stigma diameter (mm).*—<0.5.
Stigma shape.—Simple.
Ovary color.—RHS 145B (green yellow group).
Pollen amount.—Abundant.
We claim:
10 1. A new and distinct strawberry plant named 'CONSTITUTION', as herein described and illustrated by the characteristics set forth above.
